COMBINED STORAGE CABINET FOR ELECTRONIC TUBES AND STAND FOR ELECTRONIC TUBE TESTER

Harry L. Vickers, San Gabriel, Calif., assignor to Mission Tube Distributing Co., Inc., San Gabriel, Calif., a corporation of California

Filed Dec. 30, 1959, Ser. No. 58,853

Term of patent 7 years

(Cl. D80—9)

Figure 1 is a front perspective view taken from the top and right side of a combined storage cabinet for electronic tubes and stand for electronic tube tester embodying my new design;

Figure 2 is a left side elevational view thereof;

Figure 3 is a rear elevational view thereof;

Figure 4 is a top plan view thereof; and

Figure 5 is a front elevational view thereof.

I claim:

The ornamental design for a combined storage cabinet for electronic tubes and stand for electronic tube tester, substantially as shown.
